MATTRESS

Max Marsack, Milwaukee, Wis.

Application March 11, 1936, Serial No. 68,175

3 Claims. (Cl. 5—351)

The invention relates to mattresses of the class comprising an inner spring construction enclosed by edge boxing and side filling material and more particularly it relates to an improved mattress and boxing construction and method of assembling the same.

An object of the invention is the provision of improved means for connecting the edge boxing with the body filling material in order that a 10 mattress so constructed will retain its original shape and attractive appearance after long use without in any way impairing or sacrificing comfort and rest-giving qualities.

Another object of the invention is the provision 15 of an improved edge boxing or border strip for mattresses and novel means for fastening the boxing to the body of the mattress with the result that the mattress is reinforced and strengthened adjacent the border and retains a trim and substantially square edge without the necessity of providing an external or internal roll.

A further object of the invention is the provision 20 of an improved vertical boxing providing integral top and bottom lateral extensions adapted to overlap and pad the marginal portions of the spring construction and whereby the vertical portion of the boxing is held taut by the resiliency of the spring construction.

A further object of the invention is the production 25 of a square-edged mattress of the kind described provided with a suitable core, preferably of a resilient spring construction, which mattress may be readily manufactured without internal or external rolls and with a maximum 30 of machine work and a minimum of hand labor, thereby reducing the manufacturing cost as well as speeding up production, permitting an increased factory out-put without increasing manufacturing facilities.

It also has as an object, the production of a 35 mattress in which the border or boxing may be fully pre-built with a plurality of sheets or plies and in which the hand-work in the further construction or assembly of the mattress is all concealed and consequently may be done without the care or nicety required where the hand-work is exposed and in which all the mattresses will be substantially uniform in size and appearance.

Many other objects and advantages of the 40 methods and construction herein shown and described will be obvious to those skilled in the art from the disclosure herein given.

To this end my invention consists in the novel 45 construction, arrangement and combination of

parts herein shown and described and more particularly pointed out in the claims.

One embodiment of the present invention is shown for illustrative purposes in the drawings, in which:

Fig. 1 is a sectional view through an edge portion of a mattress embodying my improved construction;

Fig. 2 is a sectional view of the pre-built boxing or border strip;

Fig. 3 is a sectional view of the same taken substantially on line 3—3 of Fig. 1;

Fig. 4 is a plan view of a mattress and partial 50 sectional view to show the construction details; and

Fig. 5 is a sectional view similar to a portion of Fig. 1 illustrating another type of liner over the spring construction.

In the embodiments of the invention shown in the drawings, there is provided a pre-built border or boxing made up of a plurality of plies or sheets of material suitably secured together to constitute a unitary structure. Referring particularly to Fig. 2, in which the border is shown, the same consists of an inner ply 1 of a suitable fabric of the required width and an outer ply 4 also of suitable fabric and of the desired width, the same ordinarily being of substantially the same width as the inner ply. The ply 4, being the outer or visible one, the fabric in this ply is usually tick- 55 ing that is attractive or ornamental in appearance and of such weight as to be durable.

Arranged between the inner and outer plies 1 and 4 is a ply 2 of padding or filling and an intermediate ply 6 of suitable fabric. As will be noted, the ply 2, which is contiguous to ply 1, is of greater width than the inner ply 1 so that the ends 3 project beyond the edges of the same, as shown, and the ply 6, contiguous to ply 4, is of still greater width so that the edges 7 project beyond the 60 edges 3 of the padding 2. The side edges 5 of the outer ply 4 are preferably hemmed as shown.

In making up the boxing, the four plies are arranged substantially as shown and the same then passed through a suitable eyeleting or like 65 machine which permanently secures the several plies together by means of eyelets 8, rivets or any equivalent fastening means so that the plies are secured together at a plurality of spaced intervals, both throughout the width and throughout 70 the length and a unitary border structure obtained. While it is immaterial just what fastening means may be employed, the eyelets 8 shown have the added advantage in that they form ventilators for ventilating the interior of the mat- 75

tress as well as uniting the plies into a unitary quilted strip or border structure. These pre-built quilted border strips may be made of any desired length, in fact, they are generally made in long strips, then cut into sections each of a length to extend entirely around the edge of a mattress with the meeting ends secured together so as to form an endless border strip.

In addition to the border, the mattress body as preferably constructed, consists of the inner spring construction, a liner arranged at either face of the spring, suitable filling material at the top and bottom of the mattress and the cover ticks, the parts being suitably assembled and secured together as hereinafter described.

As shown in Fig. 1, 11 represents coil springs, a number of which are secured together by means of helicals 12, 13, etc., or the equivalents, so as to form a unitary spring structure, the outer helical 12 about the construction at the top and bottom of the coils forming an exterior edge frame which is to a certain extent, yieldable rather than rigid. It is immaterial, however, just how the spring construction is made as any of the commercial inner spring constructions or resilient fillers may be employed.

Arranged over each face of the spring is a liner 14 to which the inner ply 1 of the boxing is secured as well as the edge 7 of the intermediate ply. Also arranged over each face of the construction is the filling 18 which is covered by the top and bottom tick covers 19, the edges of which are suitably secured to the edges of the outer ply 4 of the boxing.

In making up the mattress, the inner spring is arranged on a suitable support such as a table or bench and the endless boxing strip arranged around the periphery thereof, a strip 14 of burlap, canvas or other suitable material is then arranged over the top of the spring construction to provide a liner. The edge 15 of the inner ply is then preferably stitched or otherwise secured to the adjacent edge of the liner 14 as indicated at 16. The extended edge 3 of the padding ply 2 of the border strip and the ply 6 are then wrapped or folded over the top face of the construction to overlie the face of the liner 14 and the edge 7, then laced or secured to the liner 14 as indicated at 17. Of course, any intermediate portion of the intermediate ply 6 and padding 3 overlying the liner 14 may also be secured to the burlap but this is not necessary and generally is omitted.

While the top padding or filling 18 may be applied at this time as well as the cover sheet 19, with a reversible type mattress, it is generally preferred at this stage to reverse the mattress and secure the other similar edges of the border strip plies to the other liner 14.

A suitable amount of filling material is placed over the liner 14 and extended over the overlapping or wrapped over portion of the border plies out to the outer ply 4 as most clearly shown in Fig. 1. The cover tick 19 is then applied, this sheet being first preferably hemmed as shown at 20, and the hemmed edges 5 and 20 brought together and a tape or binding 21 machine sewed about the same as indicated at 22. Then, if the opposite side of the mattress has not been fully completed, the mattress is reversed and the other side provided with the filling 18, cover sheet 19, etc.

After the mattress has been thus constructed, the tufting 23 of the usual or any suitable type may be applied in the usual manner. In some

mattresses concealed tufting may be employed but inasmuch as the tufting in itself forms no part of the present invention and is old in the art, it is not necessary to describe the same in detail herein.

In the modified construction shown in Fig. 5, a pad 24 of sisal or similar material is shown instead of the burlap 14 disclosed in Fig. 1. The sisal or the like, when used, may be in the form of a pad and quilted by stitching 25 or the like. The inner and intermediate plies of fabric may be secured to the sisal in the same manner as to the burlap. It may be mentioned that the burlap or sisal may be secured to the coils of the springs or the frame work or helicals if so desired, and it may also be mentioned that it is not essential although desired and preferred, to secure the inner ply 1 of the boxing to the liner. However, securing the inner ply to the burlap or sisal or other liner prevents any of the padding 3 from breaking loose and getting down in the springs, and securing the ply 6 likewise prevents the same from working out to the edge of the construction and any of the filler 18 from becoming displaced into the springs.

The construction described has many advantages. The boxing or border is substantial and durable. It holds its shape and at all times presents a pleasing appearance. The mattress retains its shape even after long periods of use and since the filling 18 cannot work down and become displaced below the top of the springs or work up from the bottom, the mattress edges are always maintained in order. The portions 3 do not in any way constitute rolls but do afford a very substantial wrapping or padding at the edges of the spring so that the mattress does not break down at this point and also, in the event any of the top filling 18 is displaced inwardly, the edge of the springs are padded and are not projected outwardly into the top tick or the boxing whereby the outer coverings of the mattress will become worn or frayed. By constructing the edge padding as a part of the border, it is not necessary to separately apply padding to the edges of the springs and separately secure it thereto. Being a part of the border, it is easily wrapped over and anchored to the liner, and is preferred to rolls or like devices. The fillings 2 and 18 may be of any suitable material such as cotton, hair or the like, which may be found satisfactory for the purpose.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a mattress of the kind described, an inner resilient construction, material forming a lining for the top and the bottom of the resilient construction, a boxing enclosing the vertical edges of the resilient construction, said boxing comprising a pair of contiguous outer fabric sheets, an inner fabric sheet and a layer of filling material positioned between and fastened to said inner and outer fabric sheets, said filling material and the outer fabric sheet contiguous thereto being substantially wider than the depth of the resilient construction and having their top and bottom edges turned to form marginal

covers for the resilient construction, the edges of said inner fabric sheet and the margins of said lining materials being contiguous, means fastening said inner fabric sheet to the borders of said lining material, means fastening said inturned edges to the adjacent lining material, top and bottom layers of padding material respectively covering the linings and said overlapping portions of the boxing, a pair of fabric sheets respectively forming covers for said top and bottom padding material and means fastening said cover sheets to the outside boxing sheet the width of the outside fabric sheet of the boxing being greater than the depth of said resilient construction and marginal covers and less than the overall depth of the mattress whereby the marginal edges of said cover sheets are maintained taut and convergent toward the boxing.

2. In a mattress of the kind described, an inner spring construction, a material forming linings engaging the top and the bottom of the spring construction, a quilted boxing enclosing the vertical edges of the spring construction, said boxing comprising a pair of contiguous outer fabric sheets, an inner fabric sheet and a layer of filling material positioned between and fastened to said inner and outer fabric sheets at spaced intervals, said filling material and the outer fabric sheet contiguous thereto being substantially wider than the depth of the spring construction and having their top and bottom edges inturned to form substantial covers for the marginal edges of said linings and spring construction, means fastening the edges of said inturned filling material and fabric sheet to the adjacent linings, top and bottom layers of padding material respectively covering the linings and said overlapping portions of the boxing, a pair of fabric sheets respectively forming cover ticks for said

top and bottom padding material, and means fastening said cover sheets to the outside boxing sheet, the width of the outside fabric sheet of the boxing being greater than the combined depth of the spring construction, the linings and the marginal covers and less than the overall depth of the mattress, whereby the marginal edges of said cover ticks are maintained taut and convergent toward the boxing.

3. In a mattress boxing for application to a spring construction of the kind described, an outside and an inner fabric ply, a ply consisting of a layer of filling material arranged between said plies contiguous to the inner ply but of greater width than the inner ply and projecting beyond the edges thereof, and an intermediate fabric ply interposed between the ply of filling material and the outer ply and of greater width than the filling material ply and projecting beyond the edges thereof, means securing said plies together to provide a unitary structure consisting of a plurality of fastening members arranged at spaced intervals both laterally and longitudinally of the strip of boxing and providing ventilators, the meeting ends of the boxing strip being secured together to provide an endless strip of a length to fit about a mattress body including said spring construction, said intermediate fabric ply and ply of filling material being wider than the depth of and adapted to form a substantial cover over the outer rows of the spring construction, said inner fabric ply having a width approximately equal to the depth of the spring construction and said outside fabric ply having a width greater than the depth of the spring construction and materially less than the depth of the mattress body.

MAX MARSACK.
